US0D1082734S

(12) **United States Design Patent** (10) **Patent No.:** **US D1,082,734 S**
(45) **Date of Patent:** **** Jul. 8, 2025**

(54) **ELECTRONIC DEVICE**

(71) Applicant: **Apple Inc.**, Cupertino, CA (US)

(72) Inventors: **Bartley K. Andre**, Los Gatos, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Steven P. Jobs**, Palo Alto, CA (US); **Duncan Robert Kerr**, San Francisco, CA (US); **Shin Nishibori**, Kailua, HI (US); **Matthew Dean Rohrbach**, San Francisco, CA (US); **Douglas B. Satzger**, Menlo Park, CA (US); **Calvin Q. Seid**, Palo Alto, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/964,356**

(22) Filed: **Sep. 23, 2024**

Related U.S. Application Data

(60) Continuation of application No. 29/800,030, filed on Jul. 19, 2021, now Pat. No. Des. 1,043,604, which is a continuation of application No. 29/741,885, filed on Jul. 16, 2020, now Pat. No. Des. 925,522, which is a continuation of application No. 29/635,968, filed on Feb. 5, 2018, now Pat. No. Des. 898,736, which is a continuation of application No. 29/490,408, filed on May 9, 2014, now Pat. No. Des. 809,501, which is a continuation of application No. 29/432,304, filed on Sep. 14, 2012, now Pat. No. Des. 704,701, which is a continuation of application No. 29/403,263, filed on Oct. 4, 2011, now Pat. No. Des. 672,769, which is a continuation of application No. 29/386,066, filed on

Feb. 24, 2011, now abandoned, which is a continuation of application No. 29/364,190, filed on Jun. 21, 2010, now Pat. No. Des. 634,319, which is a continuation of application No. 29/332,683, filed on Feb. 23, 2009, now Pat. No. Des. 618,678, which is a division of application No. 29/282,831, filed on Jul. 30, 2007, now abandoned, which is a continuation of application No. 29/270,887, filed on Jan. 5, 2007, now Pat. No. Des. 580,387.
